[57] **CLAIM**

The ornamental design for a playground climber and rocker, as shown.

DESCRIPTION

FIG. 1 is a top perspective view of a playground climber and rocker showing my new design;

FIG. 2 is a top plan view thereof;

FIG. 3 is a bottom plan view;

FIG. 4 is an end elevation.

The playground climber as shown in FIG. 1 is turned over to become a playground rocker.

FIG. 1

FIG. 2

FIG. 3

FIG. 4
